TOOL FOR DRIVING AND SETTING
BLIND FASTENERSJoseph C. Lang, Pittsburgh, Pa., assignor to Bocil
Corporation, Pittsburgh, Pa., a corporation of
Delaware

Application February 27, 1948, Serial No. 11,567

6 Claims. (Cl. 218—19)

1

This invention is for a tool for driving and setting specially formed fasteners of the type wherein the fastener is first driven and then a portion of it is pulled back out while another portion is held stationary to effect a deformation of the fastener after it has been driven, and wherein the excess length which is pulled out is thereafter cut off. Such a fastener is disclosed in my copending application Serial No. 5,465, filed January 30, 1948.

The present invention has for its object to provide a tool for conveniently driving the fasteners and thereafter manipulating them to effect the deformation above mentioned, and thereafter the cutting off of the excess length of the stem.

Generally stated, the invention provides a tool in the nature of a hammer having pivoted to the head end thereof a mechanism for bearing down on the head of the fastener which is to be held stationary while the other part of the fastener is pulled outwardly, said attachment also providing jaws for cutting off the projecting portion of the fastener after such portion has been pulled out. The head of the hammer also is provided with a claw or clamp to enable it to be vertically attached to the element of the fastener which is to be pulled, all as will be hereinafter more fully described.

In the drawings, Fig. 1 is a side elevation of the tool showing it engaged with a fastener which is to be operated upon, the fastener having previously been driven. The material into which the fastener is entered is shown partly in section and partly in elevation;

Fig. 2 is a view similar to Fig. 1, showing the tool manipulated to clamp the stem of the fastener preparatory to pulling the stem outwardly;

Fig. 3 is a front elevation of the view shown in Fig. 2;

Fig. 4 is a view similar to Fig. 2, part of the handle however being broken away, showing the position of the parts with the stem pulled out to de-form the inner end of the fastener;

Fig. 5 is a view partly in elevation and partly in transverse section in the plane of line V—V of Fig. 4 but with certain elements cut by said plane omitted;

Fig. 6 is a fragmentary sectional view in the plane of line VI—VI of Fig. 4;

Fig. 7 is a view similar to Fig. 4, showing the cutting off operation; and

Fig. 8 is a view similar to Fig. 5 but with the central part of the cutting plane shifted somewhat inward of the mechanism, showing the cutting off operation completed.

2

The particular form of fastener with which the present invention is especially designed to be used, and which constitutes the subject-matter of the above-mentioned copending application, is incidentally illustrated in the drawings. The fastener is especially designed to be used in fastening objects to a base panel wherein the base panel is too soft to permit the use of an ordinary nail. For example, where asbestos shingles are nailed to fiberboard insulating panels, the fiberboard is incapable of retaining the nails.

Figs. 1, 2 and 3 show the nail after it has been driven through the shingle X and the fibrous panel Y. The nail or fastener has a central stem A and two side straps B, these side straps being attached to the stem adjacent the point only. The tops of the side straps are bent laterally to form a head or abutments that limit the extent to which the nail may be driven, and the stem projects beyond the head-forming abutments.

The fastener is driven by impact similarly to a nail. Then pressure is applied to the head-forming abutments while tension is applied to the central stem. This causes the side bars or side straps to bulge outwardly as indicated at B' in Figs. 5 and 8. After this has been done, the central pin or stem is cut off flush with the head-forming abutment.

The present implement provides in a single tool a hammer for driving the fastener, a mechanism for holding the fastener in position, and for drawing the stem outwardly, and for cutting off the projecting end of the stem.

In the drawings, 2 designates the handle of the tool having a head portion designated generally as 3. It is provided with a flat driving nose or end 4 so that the fasteners may be driven in the same way that a nail is driven. The tool is preferably made of two metal stampings joined together in face-to-face relation as shown. At the end of the head opposite the striking portion 4 there is a lateral extension 5 terminating in the downwardly-extending bifurcated part 6. A spacing rivet 6a holds the bifurcated end of the member 6 from spreading. One side of the bifurcated part carries a fixed clamping plate 7. The bifurcated part also has a lever 8 pivoted thereto at 9, this lever having a curved terminal portion 10 on the inner face of which are serrations or teeth 11, this curved portion being of tapering thickness as best shown in Fig. 6.

There is an ear 12 on the offset portion 5 having a pressed-out detent or button 13 formed therein for cooperation with a socket or concavity 14 in the lever 8. When the parts are in the

position shown in Fig. 2, the detent 13 and concavity 14 are out of engagement and the lever 8 may be rocked freely. When the lever is pulled back to the position shown in Fig. 7, the detent 13 will spring into the socket 14 forming a means for holding the handle 8 against free movement. This detent means, while effective to prevent the free swinging of the lever 8, is yieldable so that the parts 8 may be readily engaged and disengaged.

The lower end of the head has a downwardly-extending projection 3a through which passes a transverse pin 15. This pin serves as a pivot to connect two opposite jaw elements 16 and 17 of a presser foot to the head. These jaw elements are of a substantial length so as to extend for a considerable distance over the surface of the work and distribute pressures therealong in the manner hereinafter more fully described. The jaw element 16 is of angle form in transverse section, having an in-turned horizontal flange 16a and an up-turned vertical flange 16b. Intermediate its ends the vertical flange 16 has an upwardly-projecting extension 18 through which the pivot pin 15 passes. This projection extends, however, above the pivot and is provided near its upper end with a detent element 19 similar to the detent element 13 previously described. It is arranged for cooperation with a recess 20 on the face of the head of the implement. In addition to the recess 20, there is another recess 20'. In Fig. 2 the projection 19 is engaged in the recess 20' to releasably hold the parts in the position shown, while in Fig. 1 the detent 19 is engaged in the recess 20. The other jaw 17 is formed similarly to the jaw 16 with an in-turned horizontal flange 17a and an up-turned flange 17b, and with an ear 17c corresponding to the projection 18, the pivot pin 15 passing through this ear. However the detent arrangement need be provided at only one side of the structure and consequently the ear 17c is of less vertical height than the extension 18 on the opposite jaw. The two jaws, being thus pivoted, provide a bifurcated pressure foot at the end of the tool adapted to be placed against the work and with respect to which the head may rock.

The inwardly-turned horizontal flanges 16a and 17a of the jaws are provided at 21 with opposed cutting edges, these cutting edges being relatively short as compared to the total length of the jaws.

The vertical flanges of the jaws are also each provided with upwardly-extending arms 22 and 23 respectively, these arms having inwardly-turned overlapping ears 24 thereon through which a pivot pin 25 passes. The arms also have inwardly-turned upper ends 26 which are beveled as shown in Figs. 5 and 8. The inwardly-turned portions 26 normally contact each other as shown in Fig. 5, at which time the cutting edges 21 are spread apart, also as shown in Fig. 5.

A lever 28 is also pivoted on the pin 15 between the two metal plates that form the head. At one end of this lever is a wedge-shaped extension 29 that extends under the over-turned arms 26 of the extensions 22 on the jaws. The other end of the lever is provided with an extension 30 which has an adjustable set screw 31 thereon. This set screw is arranged to cooperate with a transverse pin 32 in the head. By adjusting the screw 31 the range of free movement of the head relatively to the lever may be varied.

The operation of the device may now be ex-

plained. The lever 8 is held from free motion by its detent, and the pivoted presser foot comprising the two jaws 16 and 17 is also locked against free swinging movement by reason of the detent 19. The implement is then used as a hammer to drive the fastener. After the fastener has been driven, the tool is inverted and the center pin is engaged between the two jaws forwardly of the cutting edges 21. The jaws may be provided at the end remote from the fastener-engaging end with downwardly-projecting pads as indicated at 33, so that when the forward ends of the jaws are resting on the head-forming elements of the fastener, the jaws will be horizontal. The pressure is thus distributed to some extent over the surface of the asbestos shingle or other article.

At the time of engaging the pin with the jaws, the parts are in the position shown in Fig. 1. The handle 2 of the implement is then rocked to the left from the position shown in Fig. 1 to the position shown in Fig. 2. Then the lever 8 is moved to the left from the position shown in Fig. 1 to the position shown in Fig. 2. This causes the projecting end of the pin to be clamped between the serrations 11 of the curved extension 10 and the pressure plate 7. When the end of the pin has been thus clamped, the handle 2 is moved toward the right. This serves to pull the pin upwardly while the under faces of the jaws, bearing against the head-forming part of the fastener, keep the fastener as a whole from pulling out. When the parts have reached the position shown in Fig. 4, the fastener will have been set. Thereupon the lever 8 is operated to disengage the end 10 from the upper end of the pin. The tool is then shifted slightly to the left so that the protruding end of the pin will be then located between the cutting edges 21 of the two jaws. Thereafter the head of the hammer is tilted over toward the final position shown in Fig. 7. In this final rocking or tilting of the head, the pin or abutment 32 will strike the end of the adjustable screw 31 on the extension 30 of the lever 28. This causes the lever 28 to rock on its pivot, whereupon the wedge-shaped projection 29 will move from the position shown in Fig. 5 below the two overhanging arms 26, upwardly between the beveled ends of these arms. This will force the two jaws together, the jaws rocking on the pin 25. As the two jaws come together, the cutting surfaces 21 will sever the upper end of the pin. The parts are then all in position to begin the next driving and setting operation.

It will be seen that in the use of the tool the pressure used in rocking the head of the hammer to draw the stem of the fastener outwardly automatically reacts against the over-turned ends of the side bars of the fastener to keep the fastener as a whole from pulling out. The tool is also a convenient form of tool to use. The handle 2 is usually manipulated in one hand. After the operator has driven the nail, his other hand is free to manipulate the lever 8. The entire operation of driving, setting the fastener, and cutting off, can be accomplished very quickly. The tool itself, while being of rugged construction, is relatively simple and inexpensive to manufacture.

While I have shown and described one particular form of tool, it will be understood that various changes and modifications may be made within the contemplation of my invention and under the scope of the following claims.

I claim:

1. For use in connection with a fastener that has a head and a stem relatively movable to the head and connections between the head and the stem which are bowed outwardly when such relative movement between the head and the stem is effected, an implement comprising a presser foot member bifurcated so that the presser foot member may rest on the head of such a fastener while the stem may be received and pass through the bifurcation thereof, an elongated handle member with the presser foot member located at one end thereof, the adjacent end of the handle member and the foot being connected for relative tilting movement about an axis transverse to the longitudinal axis of the handle member, and a lateral extension on the handle member having a clamp that overhangs the bifurcated end of the presser foot member for releasably engaging the stem of such a fastener when the presser foot is engaged against the head of the fastener and the stem is between the bifurcated portions thereof, relative pivoting movement between the handle member and the foot member serving to move the clamp relative to the foot and thereby impart relative motion to the stem of the fastener.

2. An implement as defined in claim 1, wherein the clamp comprises a flat terminal portion of said lateral extension as one clamping element and a pivoted lever on said extension having a serrated face opposed to the face of said terminal as the other clamping element.

3. An implement as defined in claim 1 wherein the handle member has a second lateral extension extending in a direction opposed to the first, said second lateral extension having a solid plane face at the terminal thereof spaced from and projecting beyond the end of the presser foot forming a striking face with which fasteners may be hammered into the surface in which they are used.

4. An implement as defined in claim 1 wherein the bifurcated end of the presser foot is comprised of two parts which may be moved toward and away from each other, said parts being pro-

vided with opposed cutting knives that may be brought into engagement with the stem of a fastener by shifting the presser foot over the head of the fastener until the stem is between such knives.

5. An implement as defined in claim 1 wherein the bifurcated end of the presser foot is comprised of two parts which may be moved toward and away from each other, said parts being provided with opposed cutting knives that may be brought into engagement with the stem of a fastener by shifting the presser foot over the head of the fastener until the stem is between such knives, and means for moving the cutting knives toward each other by moving said handle member through a predetermined arc relative to the presser foot.

6. An implement as defined in claim 1 wherein the bifurcated end of the presser foot is comprised of two parts which may be moved toward and away from each other, said parts being provided with opposed cutting knives that may be brought into engagement with the stem of a fastener by shifting the presser foot over the head of the fastener until the stem is between such knives, there being a lever pivotally mounted on the presser foot, cooperating means on the lever and handle for forcing the knives toward each other when the lever is moved, and means on the handle member for engaging said lever to operate it to move the knives when the handle is moved through a presser arc relative to the presser foot member.
